[57] **CLAIM**

The ornamental design for a window sill frame extrusion, substantially as shown and described.

DESCRIPTION

FIG. 1 is an end elevation view of a window sill frame extrusion embodying my new design;

FIG. 2 is a top plan view of the extrusion shown in FIG. 1 shown fragmentarily to indicate indeterminate length;

FIG. 3 is a bottom plan view of the extrusion shown in FIGS. 1-2;

FIG. 4 is a front elevation view of the extrusion shown in FIGS. 1-3; and

FIG. 5 is a rear elevation view of the extrusion shown in FIGS. 1-4.

*Fig. 2.**Fig. 1.**Fig. 3.**Fig. 4.**Fig. 5.*
